UNITED STATES PATENT OFFICE.

THOMAS H. TABOR, OF ELLIJAY, GEORGIA.

QUOIT.

1,379,883.

Specification of Letters Patent. Patented May 31, 1921.

Application filed August 23, 1920. Serial No. 405,388.

To all whom it may concern:

Be it known that I, THOMAS H. TABOR, a citizen of the United States, residing at Ellijay, in the county of Gilmer and State 5 of Georgia, have invented certain new and useful Improvements in Quoits, of which the following is a specification.

This invention relates to an improved quoit which is constructed so as to prevent 10 same from flying off the usual peg which is used in the game of quoits after one of the players has made a "ringer."

The principal object of the invention is to generally improve upon quoits by providing a device which will be of extremely 15 simple, durable and inexpensive construction, one which is efficient and reliable in operation, and well adapted to the purpose for which it is designed.

20 With the above and numerous other objects in view the invention resides in certain novel features of construction, and the combination and arrangement of parts as will be hereinafter more fully described and 25 claimed.

In the drawing:

Figure 1 is a perspective view of one modification of the device,

30 Fig. 2 is a section taken on the line 3—3 of Fig. 1,

Fig. 3 is a section taken on the line 3—3 of Fig. 2,

35 Figs. 4, 5 and 6 are top plan views of various modifications of the device.

By referring to Figs. 1 to 3 inclusive of the accompanying drawing by numerals it will be seen that 1 designates the body of the quoit which is substantially shaped similar to a horseshoe. At the terminals of the 40 body portion 1 there is provided the arms 2 and 3 which converge toward each other and extend into the space surrounded by the body portion 1. It will be noted that the arm 3 is substantially shorter than the 45 arm 2.

A spring 4 is provided so as to extend 50 around the outer face of the arm 3 and around the contiguous terminal of the body 1 and extend beyond the arm 3 so as to terminate adjacent the terminal of the arm 2. In order to hold the spring in place I have 55 provided a cap 5 which incloses the terminal of the body 1 and the contiguous portion of the arm 3 as is clearly shown in the drawing. In order to hold this cap in place I have provided a rivet 6 which is passed

through the arm 3 and the body 1 as is clearly shown in Fig. 2 of the drawing.

Thus it will be seen that the spring 4 being resilient will allow the quoit to slide 60 so as to surround the peg but will prevent the quoit from accidentally sliding therefrom since the peg cannot pass outwardly between the spring 4 and the arm 2 whereas it may pass therebetween when drawing in- 65 wardly.

Referring to Figs. 4 and 5 of the drawing it will be seen that these modifications consist of the body portion 10 which has the horseshoe shaped body and the inwardly 70 converging arms 11 and 12. The arm 11 is substantially shorter than the arm 12. The modification shown in Fig. 5 will allow the peg to pass between the terminals of the arms 11 and 12 but it will be noted that 75 the peg will hit the body portion 10 at a point P or very close thereto which is situated between the center of the body portion 10 and one end thereof and thus the peg hitting this curved portion will swing 80 the peg in such a position that the rebound will cause the peg to hit the inner side of one of the arms 11 or 12 and thus prevent same from accidentally slipping off the peg. In Fig. 4 a still further precaution is pro- 85 vided by providing the band 13 which is placed around that terminal of the body portion 10 and the short arm 11 so as to hold the spring 15 contiguous with the inner edge 90 of the arm 11 and a portion of the inner edge of the adjacent terminal of the body 10. This spring 15 will have a similar action to spring 4 shown in Fig. 1 of the drawing.

In Fig. 6 I have shown a still further 95 modification which is to be used upon an ordinary horseshoe and consists of the pivoted arms 17 and 18 which are pivoted adjacent the terminals of the horseshoe 16 in any desired manner. The arm 18 is substantially shorter than the arm 17 as I have found the 100 operation in this manner to be more efficient than would be otherwise. In order to normally hold these arms 17 and 18 in a position shown in Fig. 6 I have provided a shoulder upon the underside of the arms which 105 will abut the edge of the body portion 16 when in this position thus preventing the outward movement of the arms 17 and 18. The springs 19 which may be of any pre- 110 ferred construction will allow these arms 17 and 18 to pivot inwardly so as to allow the peg to enter the interior surrounded by the

horseshoe 16 and as soon as the peg has passed thereinto the springs will force the arms 17 and 18 to the position shown in Fig. 6.

5 Owing to the simplicity of the device and the well known rules of the game of quoits it is found that from the foregoing description, taken in connection with the accompanying drawings, the construction and operation of my invention will be readily understood without a more extended explanation. As numerous changes in form, proportion, and in the minor details of construction, may be resorted to without departing from the spirit of this invention, I 10 do not wish to be limited to the construction herein shown and described other than as claimed.

Having thus described my invention what 20 I claim as new is:

1. A device of the class described comprising a horseshoe shaped body portion, arms integrally mounted upon the terminals of the body portion so as to extend into the interior of said body portion and so as to converge toward each other, one of said arms being substantially shorter than the other arm, and a spring mounted upon the short arm.
2. A device of the class described comprising a horseshoe shaped body portion, arms mounted upon the terminals of the body portion so as to extend into the interior of said body portion and so as to converge toward

each other, one of said arms being substantially shorter than the other arm, a spring provided upon the short arm, and means for holding said spring in place.

3. In a device of the class described the combination of a horseshoe shaped body, 40 arms pivotally mounted adjacent the terminals of said body, and means provided for holding said arms in a position so as to close the entrance to said body.

4. A device of the class described having 45 a substantially horseshoe shaped body, arms situated on said body so as to converge toward each other and toward the interior of the body, and means carried by one of said arms for allowing a peg to pass between the 50 arms to the interior of the body and preventing the peg from passing outwardly from the interior of the body between the arms.

5. As a new article of manufacture, a 55 quoit including a substantially horseshoe shaped body and means at the terminals of the body for allowing a peg to pass between the terminals to the interior of the body and preventing the peg from passing outwardly 60 from the interior of the body between the terminals.

In testimony whereof I affix my signature in presence of two witnesses.

THOMAS H. TABOR.
